CLAIM

The ornamental design for a faucet, as shown and described.

DESCRIPTION

FIG. 1 is a perspective view of a faucet.

FIG. 2 is a front view of the faucet depicted in FIG. 1.

FIG. 3 is a rear view of the faucet depicted in FIG. 1.

FIG. 4 is a right side view of the faucet depicted in FIG. 1, with the nozzle in an upper position.

FIG. 5 is a left side view of the faucet depicted in FIG. 1, with the nozzle in an upper position.

FIG. 6 is a top view of the faucet depicted in FIG. 1.

FIG. 7 is a bottom view of the faucet depicted in FIG. 1.

FIG. 8 is a right side view of the faucet depicted in FIG. 1, with the nozzle in an intermediate position.

FIG. 9 is a right side view of the faucet depicted in FIG. 1, with the nozzle in a lower position.

FIG. 10 is a right side view of the faucet depicted in FIG. 1, showing the support arm detached from the nozzle.

FIG. 11 is a top view of the faucet depicted in FIG. 1, with the nozzle swung to the left and in an upper position; and, FIG. 12 is a top view of the faucet depicted in FIG. 1, with the nozzle swung to the right and in an upper position.

In the drawings, the broken lines depict portions of a faucet that form no part of the claimed design.

1 Claim, 9 Drawing Sheets
